COIL WINDING MACHINE

Wayne Harman Sheley, Anderson, Ind., assignor
to General Motors Corporation, Detroit, Mich.,
a corporation of Delaware

Application January 21, 1949, Serial No. 71,972

7 Claims. (Cl. 153—64.5)

1

This invention relates to machines for winding electrical coils, for example, inter-pole coils used on dynamo electric machines.

An object of the invention is to provide a machine for winding edgewise a flat strip, the width of which is considerably greater than the thickness, around an oblong form which is rounded at its edges. During winding, the form is oscillated and rotated while the bar stock is confined in a manner such as to prevent buckling.

Further objects and advantages of the present invention will be apparent from the following description, reference being had to the accompanying drawings, wherein a preferred embodiment of the present invention is clearly shown.

In the drawings:

Fig. 1 is a side view of the machine as viewed in the direction of arrow 1 of Fig. 2.

Fig. 2 is in part a sectional view and in part a side view on line 2—2 of Fig. 1.

Fig. 3 is a sectional view on line 3—3 of Fig. 2.

Fig. 4 is a sectional view on line 4—4 of Fig. 3.

Fig. 5 is a sectional view on line 5—5 of Fig. 1.

Fig. 6 is a sectional view on line 6—6 of Fig. 2.

Figs. 7, 8, 9 and 10 are sectional views taken, respectively, on lines 7—7, 8—8, 9—9 and 10—10 of Fig. 5.

Fig. 11 is a sectional view on line 11—11 of Fig. 6.

Figs. 12 and 13 are sectional views taken, respectively, on lines 12—12 and 13—13 of Fig. 5.

Fig. 14 is a sectional view on line 14—14 of Fig. 6.

Fig. 15 is a fragmentary view looking in the direction of arrow 15 of Fig. 3.

Figs. 16—21 are diagrams illustrating the operation of the machine.

Referring to Fig. 1, a base plate 10 which is supported upon a floor in any suitable manner is attached to four rods 11 into which four rods 12 are screwed, a plate 13 being clamped between shoulders provided by rods 11 and 12. Rods 12 support a plate 14 supporting a cylinder 15 containing a piston from which a rod 16 extends. Rod 16 is connected by a clevis 17, a link 18 and a clevis 19 with a plate 20 attached to sleeves 21 which slide on two of the rods 12 thereby guiding the plate 20 for vertical movement. There is shown also in Fig. 5 plate 13 which supports a gear case comprising a bottom plate 22, a cylindrical member 23 and a cover plate 24 having a central opening 25. Plate 24 supports a plate 26 having a central opening 27. A space between plate 24 and plate 26 is occupied by a plate 28

2

which is free to slide between plates 24 and 26 and which at all times closes the opening 25.

Referring to Fig. 6, plate 13 supports a stud 30 which provides a guide for a plate 31 movable linearly and rotatively upon the plate 22, said plate 31 having an elongated hole 32 for this purpose. The head 30a of stud 30 retains plate 31 upon plate 22.

Referring to Fig. 11, an oblong gear OG, which comprises semi-circular segments 33 and rack segments 34, is located upon plate 31 by dowel pins 35 and is attached thereto by screws 36. Gear OG provides an oblong opening 37 which receives the head 30a of stud 30. Screws 39 (Fig. 5) secure to the gear support 40 for a winder form 41. The axes of segments 33 coincide with axes A and B (Fig. 16), respectively, of the cylindrical end portions of form 41. Support 40 extends into an oblong hole in a plate 42 which is urged upwardly against plate 24 (Fig. 6) by springs 43. Screws 44 secure to plate 42 a block 45 which extends through an oblong opening in plate 22 and which is provided with an oblong opening receiving the form 41. A block 46 (Figs. 5 and 7) is attached to block 45 and both these blocks provide aligned grooves 45a and 46a for receiving the bar or flat wire to be formed into a coil. The start end of the flat wire is provided with a hook bent downwardly to be received by a groove 46b in block 46. The flat wire is guided to the form by a groove 50 (Fig. 7) in the top surface of a bracket 51 which is shown in Fig. 2 as attached to plate 13. The wire is maintained in groove 50 by a plate 52 (Fig. 5) urged downwardly by a spring 53 surrounding a screw 54, the lower end of which is threaded into plate 52 and the upper end of which is guided by a bushing 55 screwed into the plate 20. Upward movement of left end of the plate 52 is restricted by a stop screw 56. Because the wire is confined in a groove, movement of gear OG is restricted to linear movement except when either one of its semi-circular segments 33 is engaged by a driving pinion 95 (Fig. 16) to be described more fully hereinafter.

As the wire is fed into the machine by operation thereof it passes between oil soaked felt strips 58 and 59 attached respectively to a lever 60 and a plate 61 attached to bracket 51. Lever 60 (Fig. 13) is pivoted at 60a on plate 61 and has a wire receiving groove 60b. Plate 61 supports an oil containing vessel 62 into which felt strip 59 extends.

The wire is cut after the winding operation by a blade 65 (Fig. 5) which cooperates with a shear-

ing edge providing a wall of a blade receiving aperture 66 provided by bracket 51. As the wire is cut by the left edge of the blade 65, its right surface 65a bends the wire about the edge 66a adjacent the hole 66 to form a hook at the end of the wire. Blade 65 (Fig. 1) is connected by link 67 with a lever 68 pivotally supported by bracket 69 and urged upwardly by spring 70.

Referring to Fig. 6, plate 20 carries taper roller bearings 72 and 73 which support a shaft 74, the lower end of which touches the block 45 when plate 20 is in the position shown in Fig. 6. Shaft 74 has a flange 75 which engages the upper end of form 41. Axial movement of shaft 74 is limited by a disc 76 which a screw 77 attaches to the shaft. Plate 20 carries a wear plate 78, the lower surface of which is flush with the lower surface of the flange 75. Screws 79 secure to plate 20 a clamp 80 which retains a plate 81 (shown in Fig. 14) which is located by pins 82. Plate 81 is shaped to provide clearance for the lower end of the shaft 74, and its thickness is substantially that of the thickness of the wire which is received between the form 41 and the edge 81a of plate 81.

The wire, while being wound around the form 41 is confined between an upper relatively fixed member, which includes disc 75 and wear plate 78, both engaging the top surface of form 41 when frame 20 is down, and a lower or relatively movable member provided by block 45. Block 45 directly engages the wire of the first turn and springs 43 operate to cause the block to urge the first turn and succeeding turns upwardly toward the disc 75 and the wear plate 78. The lower end of shaft 74 provides a smaller disc which, in conjunction with surface 81a (Fig. 16) of plate 81, provides means for causing the wire to conform to the cylindrical portion of the form 41 as it is rotated.

Referring to Fig. 6, the parts enclosed within the gear case are lubricated by oil introduced through an aperture 83 closed by a plug 84. This oil may be drained through an aperture 85 normally closed by a plug 86. The gear case contains a bracket 90 located by dowel pins 91 relative to plate 22 and secured to plate 13 by screws 92 (Fig. 9). A block 93 occupies the space between one side of bracket 90 and the wall 23 to transmit side pressure. The gear OG meshes with a gear 95 keyed to a shaft 96 which is journaled in ball bearings 97 and 98 supported respectively by bracket 90 and plate 13. For more quiet operation, these meshing gears have helical teeth.

Referring to Fig. 2, shaft 96 is journaled also in bearing 99 supported by a bracket 100 supported by a bracket 101 supporting bearings 102 for a shaft 103. Shafts 96 and 103 are connected by bevel gears 104 and 105 attached respectively to these shafts. Shaft 103 is connected with a driven member of a clutch 119, the driving member of which is connected by a coupling 111 with a power driven shaft 112. The connection between the driven members of the clutch is controlled by a disc 115 which, in response to arresting its motion, effects disengagement of the clutch and which, in response to its release, effects engagement of the clutch. A well known clutch of this type is the Hilliard clutch.

As shown in Fig. 4, disc 115 is notched to provide a surface 116 engageable with a stop plunger 117 guided by lever 118 pivoted at 119 on a bracket 120 attached to base plate 10. A spring 75

121 urges the plunger upwardly and its upward movement is limited by plate 122 attached to lever 118 by a screw 123. Lever 118 is urged clockwise (Fig. 4) by a spring 124 so that the lever tends to ride on the disc 115 which rotates counterclockwise so that it is ready to stop motion of the disc 115 by engagement of plunger 117 with the surface 116 of the disc. Counterclockwise motion of lever 118 is effected by a pedal 125 pivoted at 126 on a bracket 127 attached to plate 10 and urged upwardly by a spring 128 surrounding a rod 129 passing through a hole 130 in plate 10 and a hole 131 in pedal 125. A nut 132 threaded on rod 129 retains a washer 133 which retains the pedal 125. The spring 128 is confined between a washer 134 supported by plate 10 and a washer 135 retained by head 136 of rod 129. Lever 118 is connected by a pin 140 with a clevis 141 connected with a rod 142 which passes through a hole 143 in pedal 125 and is engaged by nut 144 which retains a washer 145. When pedal 125 is moved downwardly, motion is transmitted by rod 142 of lever 118 to cause it to move counterclockwise so that disc 115 is released and the clutch engages.

The lever 118 is controlled also by a timing mechanism which comprises a sprocket 150 (Figs. 2 and 3) attached to shaft 96 and connected by chain 151 with a sprocket 152 and engaging an idle sprocket 153 journaled on the screw 154 carried by bracket 155 which, as shown in Fig. 15, is supported by screw studs 156 and 157 attached to plate 13. Bracket 155 pivots about stud 157 in order to position the sprocket 153 to tighten the sprocket chain 151. The bracket is retained in adjusted position by tightening the nut 158 on the stud 156 which passes through an arcuate slot 159 of bracket 155, said slot having its geometrical center at stud 157. The tightening of nut 158 clamps the bracket 155 against a spacer 160 which in turn is clamped against the plate 13.

Sprocket 152 is attached to a shaft 162 which, as shown in Fig. 1, is journaled in bearing members 163 and 164 attached, respectively, to plates 13 and 10. Sprocket 152 drives a worm 165 meshing with a worm gear 166 which, as shown in Fig. 3, is attached to a shaft 167 journaled in bearings provided by brackets 168 and 169 attached to plate 10. Shaft 167 is connected with a disc 170 (Fig. 4) having arcuate slots 171 each for receiving a screw 172 threaded into a cam 173 thus providing for adjustment of the cam 173 relative to shaft 167. The direction of rotation of the cam 173 is clockwise in Fig. 4. Cam 173 provides a high land or dwell 173a, a slope 173b, a low land 173c and a slope 173d. Cam 173 is engaged by a roller 174 supported by a lever 175 pivoted on a screw 176 attached to bracket 169 and connected by link 177 with lever 118. When roller 174 engages low land 173c, lever 118 is permitted to move by spring 124 into contact with disc 115 in preparation for arresting movement of said disc. When roller 174 engages high land 173a, the plunger 117 is retracted from the disc.

Preparatory to winding a coil from a new supply of wire, the plate 20 is lowered to the point shown in Fig. 5, and the wire is passed through the groove 58 and a little past the opening 66 (Fig. 5). The blade 65 is manually lowered so as to shear the wire, remove the excess and to cause the edge portion thereof to be bent down around the corner 66a to form a hooked end portion. The plate 20 is raised by admitting pressure fluid to the lower end of the cylinder 15 to permit by manual operation the pulling of the

wire through the groove 50 to the left (Fig. 7) and the placing of the hooked end of the wire in the notch 45b of block 45. Then plate 20 is lowered to the position shown in Fig. 5 by admitting pressure fluid to the upper end of cylinder 15. Pedal 125 (Fig. 4) is depressed for a time sufficient to cause engagement of slope 173d and a part of high land 173a of cam 173 with roller 174, thereby effecting retraction of plunger 117 and release of disc 115 and the transmission of power to shaft 103 by clutch 110. Then the pedal 125 is released and coil winding proceeds for a time sufficient to complete the winding of the coil and when the coil is wound the slope 173b will have passed the roller 174 to allow it to move upon the low land 173c so that the stop plunger 117 is ready to receive the surface 116 of disc 115 to arrest movement thereof so that operation of the machine ceases.

Fig. 16 represents the condition of the machine when winding starts. As gear 95 rotates counterclockwise, gear OG moves successively into the positions shown in Figs. 16 through 21 to cause a coil of wire to be formed. As the wire W is bent edgewise, it is caused to conform to the form 41 by virtue of the lower end of the shaft 74 and the surface 81a of plate 21. In order to show clearly the different positions of the form 41, the geometrical centers of the cylindrical end surfaces are marked A and B respectively. Fig. 21 shows that one turn of the wire has been wound following the position of gear OG shown in Fig. 21 which moves to the position shown in Fig. 16 and the cycle is repeated. Each time gear OG operates through one cycle, that is, from Figs. 16 to 21 and back to Fig. 16 position, the shaft 103 (Fig. 2) makes two revolutions and cam 173 turns $1/10$ of a revolution, this ratio of movement being that required for a particular coil which, for example, is to have $9\frac{1}{2}$ turns. Therefore, the machine is stopped automatically when the winding mechanism is in the position shown in Fig. 19 which is the position it has at the end of the first half turn and obviously at the end of the $9\frac{1}{2}$ turns. In this position of the mechanism both ends of the leads of the coil extend from the same end thereof, this arrangement of the leads being required for convenience in making electrical connections. When the winding has proceeded nearly to the completion of the $9\frac{1}{2}$ turns, the slope 173b (Fig. 4) of cam 173 passes by the roller 174 so that it can engage the low land 173c, thereby permitting the lever 118 to be drawn by spring 124 against the clutch disc 115 so that the clutch will be disengaged by the time $9\frac{1}{2}$ turns are completed and the winding mechanism is in the status indicated in Fig. 19. Lever 68 (Fig. 1) is moved down to cause the blade 65 to sever the coil from the supply wire and to bend the end of the supply wire to form a hook. Plate 20 is then elevated so that the finished coil can be removed from the form. During the winding of the coil, the turns of the coil are piled successively, one upon the other, thereby forcing the block 45 and plate 42 downwardly against the action of springs 43. When plate 20 is raised, springs 43 cause the coil to be stripped from the form 41. The winding of the bare wire upon the coil causes the wound wire to change in characteristic from initially relatively soft to a somewhat hard or tempered condition in which it has resiliency. Therefore, when it is stripped from the winding form, the coil tends to unwind itself or fan out. The coil is then annealed to remove its temper

so that its turns can easily be aligned so that the coil can be placed around a magnetizable core having a cross sectional shape like the winding form 41.

Before starting to wind the next coil, the winding mechanism must be moved from the status shown in Fig. 19 to the status shown in Fig. 16. This is effected by holding the pedal 125 in down position just long enough for the plunger 117 to be retracted from the surface of disc 115 and the clutch to be engaged and the shaft 103 to start turning. Thus the pedal is released so that the motion of the disc 115 will be arrested and the machine will stop at the end of one revolution. The low land 173c (Fig. 4) is long enough to permit this last or 20th revolution of shaft 103 without any control by the cam 173, said cam having turned $1/20$ revolution clockwise from the position shown in Fig. 4. The mechanism is then ready for the next winding operation.

The valve for controlling the admission of pressure fluid to the ends of the cylinder 15 is not shown. Any suitable manually operated valve may be used for this purpose.

While the embodiment of the present invention as herein disclosed, constitutes a preferred form, it is to be understood that other forms might be adopted.

What is claimed is as follows:

1. A machine for winding an oblong coil of flat wire comprising an oblong form having parallel side surfaces and cylindrical edge portions, mechanism for causing the form to move lengthwise or in a direction parallel to its side surfaces, then to rotate 180° about the axis of one of its edge portions, then to move lengthwise in the opposite direction and then to rotate 180° about the axis of the other of its edge portions, this cycle of movement being repeated until the required number of coil turns have been wound, members for confining the wire flatwise, one being relatively fixed and the other relatively movable, spring means urging the movable member toward the fixed member, means for limiting the initial spacing of the members to a distance substantially equal to the thickness of the wire and for causing the wire to be maintained against the cylindrical portions of the form during rotation thereof whereby the wire is bent edgewise, the movable member moving away from the fixed member as additional turns of wire are wound and means for advancing the relatively fixed member into position adjacent the form for the coil winding operation and for retracting it after the coil is wound to permit removal of the coil from the form.

2. A machine according to claim 1 in which the relatively fixed member includes a disc rotatable on an axis parallel to the axes of the cylindrical edge portions of the form, said disc, when advanced, engaging the form and in which said means includes a smaller disc coaxial with and rotatable with the first disc and a plate engageable with one edge of the wire and extending close to the smaller disc.

3. A machine according to claim 1 in which the movable member is a block which surrounds the form and is movable therealong and which is provided with a recess for receiving a bent portion of the start end of the wire whereby the wire is initially anchored to the block.

4. A machine according to claim 1 in which there is a frame movable in a direction parallel to the axes of the cylindrical portions of the form, in which the relatively fixed wire-confining mem-

its semi-circular segments are engaged by the pinion.

7. A machine according to claim 1 in which the mechanism is power driven through a clutch, and in which a clutch control is provided for effecting clutch engagement by a manual operation and clutch disengagement automatically after a predetermined number of mechanism cycles plus one-half cycle which provides for completion of a coil with the leads thereof extending in the same direction, and, following a second manually effected clutch engagement, for effecting clutch disengagement automatically after completion of the last mechanism cycle to bring the machine into status for the next winding operation.

WAYNE HARMAN SHELEY.
